UNITED STATES PATENT OFFICE

WILLIAM C. RASTETTER, OF FORT WAYNE, INDIANA

FOLDING CHAIR

Application filed March 20, 1931. Serial No. 524,043.

This invention relates to improvements in folding chairs, and the object of the improvement is to provide a chair having foldable members and means in connection therewith by which the unfolding movements of said members are limited, and are so disposed as to be out of the way from obstruction and free from liability of being bent and operation thereof impaired.

The chair embodying the present invention in part is similar to that set forth in my previous application, Sr. No. 485,009, filed September 29, 1930 for Folding chairs, and is distinguished therefrom particularly in the means whereby the folding movements of the seat and rear legs are limited and in several other respects as will appear in the following description.

An illustrative embodiment of the invention is shown in the accompanying drawings, in which:

Fig. 1 is a side elevation of a chair structure in which the invention is embodied, the chair being in extended position and portions thereof being broken away;

Fig. 2 is a detail view upon an enlarged scale of the connection between the stop-rod and the seat-frame, portions being in section;

Fig. 3 is another detail view upon an enlarged scale showing the manner of securing the seat-frame on the seat-rod, parts being in section;

Fig. 4 is a rear elevation of the chair in folded position;

Fig. 5 is a detail view upon an enlarged scale of a guide shown in vertical section and a stop-rod in connection therewith;

Fig. 6 is an elevation upon an enlarged scale of the guide showing the outer face thereof, a portion being broken away; and

Fig. 7 is an enlarged detail fragmentary view of the stop-rod and cross brace for the rear legs.

The chair shown in the illustrative embodiment of the invention is comprised of a main frame 1 having side members 2 constituting forelegs, there being secured in the upper end portions of said frame a back-rest 3. In said forelegs is secured a trans-

versely disposed seat-rod 4, and upon said seat rod is pivotedly supported a seat frame 5 preferably formed of a single strip bent so as to have parallel side members 6, in which is permanently secured a seat 7.

Upon the inner face of each side member is disposed a plate 8 through which the rod 4 extends and against which the corresponding upper ends of a cross-brace 9 bear, said rod 4 also extending through said upper ends of the brace. A tubular spacer 10 is positioned upon the rod 4 with its respective ends extending to the corresponding upper ends of said cross-brace. Upon the outer face of each side member 6 of the seat-frame is disposed a plate 11 through which the rod 4 extends, each plate having at its rear end opposed ears 12 and 13 between which the corresponding ends of the side members are secured by means of a rivet 14. Upon the rod 4 between the plate 11 and the adjacent inner face of the corresponding foreleg 2 is disposed a tubular spacer 15 whereby the seat-frame is held centrally within the frame 1 spaced from the forelegs. The lower ends of the braces 9 are secured respectively to the inner faces of the forelegs 2, as indicated by 9', so that the cross-brace sustains the seat-frame in its central position relative to the frame 1.

To each foreleg 2, upon the inner face thereof at a point above the seat-rod 4 is pivoted, as indicated by 16, a rear leg 17, and each rear leg is connected with the corresponding side member 6 of the seat-frame by 18, the forward ends of said links being pivoted to the corresponding sides of the seat-frame through the plates 11 thereon at points between the seat rod 4 and the rear ends of the side members 6, as indicated by 19. The opposite ends of said links are pivoted to the corresponding rear legs upon the inner faces thereof as indicated by 20. When the seat is turned pivotedly upon the seat-rod 4 folding or unfolding movement is imparted to the rear legs 17 accordingly.

To the lower end portions of each rear leg upon the inner face thereof is disposed a guide member 21 having a longitudinally

slotted embossment 22, the upper end of which is closed and the lower end of which is open, and a cross-brace 23 is secured together with said guide members to said rear legs by means of rivets 24.

Each of the plates 11 has formed upon its outer face adjacent the rear end thereof a perforated embossment 25 in which is pivotedly secured a stop-rod 26, the upper end of which rod has formed thereon a bent prong 27 that engages in the corresponding embossment so that the rod has pivotal connection with the rear end of the seat-frame. The opposite end of each stop-rod 26 has an elbow 28 that projects through the slot 29 of the embossment 22 on the corresponding guide member, and upon the extremity of the elbow is formed a head 30 which is disposed within the embossment and has sliding movement therein when the rod is moved vertically relative to the guide member. Each upper arm of the brace 23 has a slot 31 made therein through which the rod 26 has sliding movement, said slot being elongated to permit the prong 27 to be passed therethrough, and the lower end of the embossment being open to permit the head 30 to be inserted therein when the rod is being assembled in the chair structure.

30 A feature of the invention is the relative arrangement of the cross-brace 9, the forelegs 2, the seat-rod 4 and the seat-frame 5 whereby the seat-rod receives support from the forelegs and the cross-brace and the sides 35 6 of the seat-frame are suspended upon the rod respectively at points between the upper ends of the cross-brace and the forelegs correspondingly. In this manner the seat-rod is sustained fixedly in position by the forelegs and the cross-brace whereby an unyielding support for the seat frame is afforded and bending of the seat rod is obviated when the chair is subjected to the weight of the occupant.

40 45 I claim:

1. In a folding chair, a main frame constituting a back and forelegs, rear legs piv-

oted to said main frame, a seat rod the ends of which are secured in said main frame at points therein below the rear by pivots, a seat-frame pivoted on said seat-rod, means connecting the seat-frame and the rear legs for imparting movement to said rear legs rearwardly as the seat is extended for use, a guide member having a longitudinally slotted embossment on the inner face of each rear leg, a cross-brace connecting said rear legs the upper arms of which have each a slot therein, and stop-rods pivoted to the rear end of said seat-frame extending respectively through the apertures in said cross-brace and having a head slidably engaged in the embossment of the corresponding guide member in which it is confined and has limited movement.

2. In a folding chair, a main frame constituting a back and forelegs, rear legs pivoted to said main frame, a seat rod the ends of which are secured in said main frame at points therein below the rear leg pivots, a seat-frame pivoted on said seat-rod, means connecting the seat-frame and the rear legs for imparting movement to said rear legs rearwardly as the seat is extended for use, a guide member having a longitudinally slotted embossment on the inner face of each rear leg, and stop-rods pivoted to the rear end of said seat-frame each having a head slidably engaged in the embossment of the corresponding guide member in which it is confined and has limited movement.

3. In a folding chair, a main frame, a seat pivoted in the frame, a rear leg structure pivotedly connected in the frame at points above the seat pivots, a guide member disposed upon each of the legs of said rear leg structure having a longitudinal slot, and stop-rods pivoted on the rear end of said seat, the lower end of each of said stop-rods being confined in the corresponding guide and having limited sliding movement therein.

WILLIAM C. RASTETTER.
